UNITED STATES PATENT OFFICE.

HARRY PICKHARDT, OF NEW YORK, N. Y., ASSIGNOR TO THE PHOENIX GLASS COMPANY, OF PITTSBURGH, PENNSYLVANIA, A CORPORATION OF WEST VIRGINIA.

LIGHTING-FIXTURE.

1,253,881.

Specification of Letters Patent. Patented Jan. 15, 1918.

Application filed February 13, 1915. Serial No. 7,976.

To all whom it may concern:

Be it known that I, HARRY PICKHARDT, a citizen of the United States, residing at New York, in the county of New York and 5 State of New York, have invented a certain new and useful Improvement in Lighting-Fixtures, of which the following is a specification.

My invention relates to electric lighting 10 fixtures and is designed as an improvement on the patent granted to George F. Wehr, No. 1,040,072, reference to which discloses the fact that the said patent covers a lamp in which the outer shade rests upon the 15 upper end of an outwardly flaring portion of glass.

My invention is intended to be used either 20 in connection with a portable lamp such as is shown in the said patent, and it may also be used for wall brackets and candelabras, and is intended to be used where a greater amount of light is desired than can be obtained from a lamp constructed in accordance with the said patent and yet to 25 serve the semi-indirect lighting effect of the invention described by the said patent.

My means of accomplishing the foregoing objects may be more readily understood by having reference to the accompanying drawing which is hereunto annexed and is a part of this specification, in 30 which:

The drawing represents a vertical sectional view of my invention as applied to 35 a table lamp, although it will be obvious from the hereinafter contained description as hereinbefore stated, that it can be used with equal desirabilities on candelabra or wall bracket.

40 Similar reference numerals refer to similar parts throughout the entire description.

As shown in the drawing, the invention is applied to a standard 1, which is provided with a socket 2, of the usual construction 45 for the ordinary electric light bulb.

Around the base of the bulb, and at the top of the socket, I provide a shade holder 4,

in which rests the lower edge of an inverted shade 5, this shade preferably being constructed of translucent glass so as to prevent the direct lighting, thereby avoiding the glare which is so tiresome to the eyes and giving the softening effect which is so much desired in lighting effects at the present time. The shade 5 flares upwardly 50 and outwardly and its upper edge supports the shade 6, which flares downwardly and outwardly, and is provided with central openings 7. The shade adjacent this opening rests directly upon the top of the shade 5, which permits the light from the bulb to be reflected by means of the translucent reflector shade 5 up against the ceiling where it will be thrown downwardly lighting the room. 65

The result of this construction is that by this very simple expedient I absolutely remove the glare of the light in the eyes of the user, and yet attain the increased lighting effect by means of the opening 7, at 70 the top of the shade 6.

Having described my invention what I regard as new and desire to secure by Letters Patent is:

A semi-indirect light comprising the combination with the lamp and its stand, of an upwardly and outwardly flaring shade opened at the top, an outwardly and downwardly flaring shade having a central opening therein, the upper edges of the flared 75 portion extending over the top of the shade, said outwardly and downwardly flaring shade having an internal annular enlargement adapted to engage the upwardly and outwardly flaring shade for holding the 80 outwardly and downwardly flaring shade against movement with relation to the upwardly and outwardly flaring shade. 85

In witness whereof I have signed the foregoing specification.

HARRY PICKHARDT.
